(74) Attorney, Agent, or Firm — Burris Law, PLLC

(57) **CLAIM**

The ornamental design for a massage appliance, as shown and described.

DESCRIPTION

FIG. 1 is a perspective view of the massage appliance;
FIG. 2 is a right side view thereof;
FIG. 3 is a left side view thereof;
FIG. 4 is a front view thereof;
FIG. 5 is a rear view thereof;
FIG. 6 is a top view thereof; and,
FIG. 7 is a bottom view thereof.

1 Claim, 7 Drawing Sheets
